AUGUSTO DINA, OF JERSEY CITY, NEW JERSEY, ASSIGNOR TO INTERNATIONAL PROJECTOR CORPORATION, OF NEW YORK, N. Y., A CORPORATION OF DELAWARE

ADJUSTING APPARATUS FOR MOTION PICTURE PROJECTION MACHINES

Application filed April 18, 1928. Serial No. 271,092.

This invention relates to pedestals for motion picture projection machines, and more particularly to a new and improved support for the motor and the pedestal lever adjusting screw thereof.

In machines of the above character it is essential to provide adjusting means for varying the angle of elevation of the projecting apparatus whereby the operator may control the same with a minimum number of operations. The adjusting means must furthermore be of solid construction to prevent the apparatus from vibrating and causing a shaking of the picture. The motor support should preferably be in an accessible position and provided with means for adjusting the relative position of the motor and the driving apparatus in order to accurately align the parts with respect to the driving belt. Furthermore, the motor should be in such position that the various controls and operating parts of the mechanism are not interfered with thereby.

In accordance with the present invention, a single bracket is employed for supporting the pedestal lever adjusting screw and the motor table. This bracket is securely fastened to the pedestal at a plurality of points and is of a sufficiently solid construction to prevent unauthorized movement of the parts. The motor table is adjustably attached to the bracket and a limited vertical movement thereof is permitted. The motor is secured to the table in such manner that it may be moved transversely thereof, whereby any desired combination of vertical and transverse movement may be obtained for securing the same in its proper location.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connec-

tion with the accompanying drawings forming a part thereof, in which

Fig. 1 is a side elevation of a pedestal showing the support for the motor and for the pedestal lever adjusting screw;

Fig. 2 is a rear elevation thereof, partly in section, showing the details of the pedestal lever;

Fig. 3 is a section taken along the line 3—3 of Fig. 2 showing the pedestal and supports;

Fig. 4 is a section taken along the line 4—4 of Fig. 1 showing the pedestal lever adjusting screw;

Fig. 5 is a section taken along line 5—5 of Fig. 1 showing the connecting yoke;

Fig. 6 is a section taken along the line 6—6 of Fig. 1 showing the motor table;

Fig. 7 is a section taken along the line 7—7 of Fig. 8 showing the means for clamping the motor table to the supporting pin; and

Fig. 8 is a section taken along the line 8—8 of Fig. 1 showing the clamping means for the motor table.

Like reference characters denote like parts in the several figures of the drawings.

In the following description and in the claims parts will be identified by specific names for convenience, but they are intended to be as generic in their application to similar parts as the art will permit.

Referring to the drawings more in detail, a pedestal 10 is shown provided with an enlarged base 11, by means of which it is supported and having a pedestal lever 12 pivoted to the top thereof by bearing 13. Pedestal lever 12 is provided with a plurality of tubular members 14 (Figs. 1 and 2) in which pin 15 is secured, and a plurality of members 16 engaging pin 17. Lamp house supporting arm 18 is journaled by bearings 19 on pin 15 and carries lamp house plate 20 by means of which the lamp house is supported in any well known manner. A guiding arm (not shown) may be journaled on pin 17 for controlling the horizontal angle of the lamp house. The particular form of lamp house support, however, forms no part of the present invention, and will not be described in detail.

Bracket 21 is provided with a pair of engaging surfaces 22, by means of which it is secured to pedestal 10 as by bolts 23. Said bracket is provided with a downwardly extending tubular bore, in which pin 24 is secured by bolts 25 which extend through drilled holes in the outside of said bracket and are threaded into said pin. Pin 24 is provided with a tapered keyway 26 which is engaged by cooperating key 27 (Figs. 7 and 8) for securing the motor table thereto.

Motor table 29 is formed with a motor supporting surface 30 having a pair of elongated slots 31 therein, through which wing screws 32 may be passed for securing motor 33 thereto. The transverse position of said motor may be varied by loosening wing nuts and moving the same in elongated slots 31.

Tubular section 34 is integrally formed with motor table 29 and is suitably drilled to pass over pin 24. Wing nuts 35 are threaded in tubular section 34 and bear against key 27 for forcing said key into firm engagement with keyway 26 and securing the motor table. Key 27 is also provided with a wedge shaped slot 36 which is adapted to be engaged by bolt 37 having a cooperating wedge shaped end and threaded into tubular section 34. Bolt 37 may be adjusted to hold key 27 firmly in keyway 26 and prevent the same from moving relatively to tubular section 34 when wing nuts 35 are loosened.

Pedestal lever adjusting screw 40 is inserted in a tubular bore in bracket 21 and secured therein between shoulder 41 and nut 42. Pin 43 may also be passed through bracket 21 and screw 40 for further securing the assembly and preventing turning movement of said screw. Collar 44, provided with an elongated hub 45 and having hand wheel 46 forming a part thereof, is threaded upon adjusting screw 40 and adapted to be moved longitudinally of said screw by means of said hand wheel.

Yoke 47, which is firmly secured to pin 15, is provided with a pair of guiding studs 48 in the two arms thereof which engage collar 44 and determine the angular position of the pedestal lever 12. Studs 48 are secured in yoke 47 in any convenient manner as by cap nuts 49. Clamping wheel 50 is carried upon shaft 51 which is journaled in arm 52 on yoke 47 and threaded into arm 53 thereof. Shoulder 54 is adapted to bear against the face of arm 52 and permit the two arms to be bent together for clamping collar 44 between guiding studs 48 whereby relative movement of the parts is prevented after they have been adjusted to the desired position. Lock nut 55 (Fig. 1) may also be employed for preventing movement between hub member 45 and adjusting screw 40.

In order to adjust the angle of elevation of the projecting apparatus, set screw 55 and hand wheel 50 are loosened and adjust-

ing wheel 46 is turned, whereby collar 44 is moved longitudinally of screw 40. Yoke 47 which is in engagement with collar 44 is moved therewith and causes pedestal lever 12 to pivot about bearing 13 on pedestal 10. After the adjustment has been obtained the parts may be locked by clamping guiding studs 48 against collar 44 and by threading lock nut 55 against adjusting wheel 46.

Motor 33 may be adjusted in elevation by 75 loosening wing nuts 35 thereby permitting key 27 to disengage from keyway 26. The wedge shaped key provides a comparatively large contacting surface with the keyway whereby the friction thereof is considerably increased. When the key is forced into firm engagement with the keyway by wing screws 35 it provides a particularly rigid locking means for table 29.

By supporting the motor table and the 85 adjusting screw from a single bracket the total number of parts required for the machine is reduced. The bracket is provided with a plurality of contacting surfaces whereby it may be rigidly secured to the 90 pedestal and by reason of which a particularly solid construction is effected.

It will be seen that in general there are many advantages in this type of construction which makes for facility of adjustment 95 and which permits positioning the adjusting mechanisms where they are entirely out of the way and not apt to be hit by the operators. One of the particular features is that the adjustment of the motor table permits easy and ready taking up of any excess slack in the driving belt. It also enables the operator to install a new belt without straining it, as he may raise the table, place the belt in position and then lower the table 105 to provide a correct tension in the belt.

It will also be seen that the various parts of the bracket, adjusting rod 40 and the pin 24 may be made integral if desired, or if produced as individual elements they may 110 be joined together in any satisfactory manner or may be directly joined to the pedestal, but any of these mechanical equivalents are to be considered as being within the scope of the invention.

While certain novel features of the invention have been shown and described and are pointed out in the annexed claims, it will be understood that various omissions, substitutions and changes in the forms and details 120 of the device illustrated and in its operation may be made by those skilled in the art without departing from the spirit of the invention.

What is claimed is:

1. A motor support comprising a bracket, means for securing said bracket to a pedestal, a downwardly extending post associated with said bracket, said post being provided with a wedge shaped keyway, a motor table 130

- comprising a flat portion adapted to receive said motor and a tubular portion adapted to engage said post, a wedge shaped key secured in said tubular portion in engagement with said keyway, and means for varying the pressure of said keyway for securing the assembly in any desired position, said key having a wedge shaped slot therein and a screw threaded bolt in said tubular section and having a wedge shaped end adapted to engage said slot for preventing movement of said key relatively to said tubular portion when the pressure thereon is released.
2. A motor support comprising a bracket, means for securing said bracket to a pedestal, a downwardly extending post associated with said bracket, said post being provided with a wedge shaped keyway, a motor table comprising a flat portion adapted to receive said motor and a tubular portion adapted to engage said post, transversely extending elongated slots in said flat section, means passing through said slots for securing said motor thereto, a wedge shaped key secured in said tubular portion in engagement with said keyway, and means for varying the pressure of said key in said keyway for securing the assembly in any desired position.
3. In combination with a motor, a support therefor comprising a pin, a motor table carried by said pin, means including a wedge shaped key and cooperating keyway for slidably securing said table to said pin, and said key having a wedge shaped slot for preventing longitudinal movement of said key with respect to said motor support and a member carried by said support and cooperating with said slot.
4. A support for a projection machine comprising a U-shaped bracket having a pair of flat surfaces adapted to be attached to a pedestal, said bracket having an angularly extending bore provided with a shoulder adapted to receive an adjusting screw for controlling the angular position of said machine and having a downwardly extending tubular bore adapted to receive a pin carrying a motor table.
5. A support for a projection machine comprising a bracket having means for attachment to a pedestal, said bracket having an angularly extending bore adapted to receive an adjusting screw for controlling the angular position of said machine and having a downwardly extending bore adapted to receive a pin carrying a motor table.

AUGUSTO DINA.
